UNITED STATES PATENT OFFICE.

CLIVE M. ALEXANDER, OF WAXAHACHIE, TEXAS.

BUBBLE CAP FOR GAS AND LIQUID CONTACT APPARATUS.

Application filed July 23, 1926. Serial No. 124,340.

This invention relates to improvements in gas and liquid or vapor and liquid contact apparatus. More particularly, the invention relates to improvements in bubble caps such as are used in fractionating towers, absorbing towers, scrubbing towers and the like where it is desired to contact a vapor or gas with a liquid. Towers for these several purposes are commonly made up of a series of pans or trays in each of which a number of nipples are arranged, caps being arranged over the nipples to compel gas or vapor rising through the nipple to bubble under the rim or through openings in the side walls of the cap through a pool of liquid maintained on the pan or tray, overflow connections also being provided to maintain a liquid level at or above the upper edges of the openings through which the gas or vapor is discharged and to permit excess liquid to flow to the next lower pan or tray in series. Various shapes of bubble caps have been employed for this purpose, some of them being supported on the rim of the cap and some by a connection between the crown of the cap and the nipple over which it is placed or the tray or pan itself.

This invention provides an improved bubble cap of special value and application in apparatus of the type just described which has several advantages. The improved bubble cap of the invention has a high ratio between the area of the openings for the escape of gas or vapor and the space occupied by the cap, making possible a larger capacity per pan or tray of a given area. The improved bubble cap of the invention also promotes more effective distribution of the gas or vapor escaping therefrom, making it possible to secure better contact between liquid and gas or vapor.

In the improved bubble cap of this invention, the side walls of the cap are provided with alternate extensions and depressions and openings for the escape of gas and vapor from beneath the cap are arranged through both extended and depressed portions of the side walls. A plurality of series of openings for the escape of gas or vapor from beneath the cap is thus provided, the several series of openings being arranged to discharge the gas or vapor at substantially different distances from the vertical axis of the bubble cap. A high ratio as between the total width of the opening and the mean perimeter of the bubble cap is thus main-

tained, and distribution affording intimate contacting is promoted by discharge of the gas and vapor at more or less separated points and in a manner to insure fine division of the gas and vapor.

The present invention is particularly applicable in connection with bubble caps made by casting and adapted to be supported on the pan or tray by the rim of the cap itself. The present invention makes it possible to fabricate the bubble caps in this manner with a relatively large area of opening for the discharge of gas or vapor with respect to the size of the cap without sacrifice of the strength of the cap or its ability to resist handling or cooling strains involved in casting through any necessity of making parts of the cap too light.

Two forms of bubble caps embodying the invention are diagrammatically illustrated in the accompanying drawing, and the invention will be further described in connection therewith, but it will be understood that while the invention is exemplified by this further description and illustration it is not limited thereto. In the drawing

Fig. 1 is an elevation, partly in section, of a bubble cap embodying the invention,

Fig. 2 is a plan view, with parts broken away, of the bubble cap shown in Fig. 1,

Fig. 3 is an elevation, partly in section, of a modified form of bubble cap embodying the invention,

Fig. 4 is a plan view, with parts broken away, of the bubble cap shown in Fig. 3, and

Fig. 5 is a diagrammatic representation, in elevation and partly in section, of a tower illustrating the use of the improved bubble cap of the invention in apparatus of this character.

Referring to Fig. 5, the tower illustrated is of conventional construction such as is commonly used for fractionation, absorption or scrubbing operations. It consists of a series of trays 6 through which nipples 7 extend. Bubble caps 8 are arranged over the nipples so that gas or vapor rising through the nipples is compelled to bubble through liquid maintained at a level above the discharge openings of the bubble caps by means of run-back connections 9 which also serve to convey excess liquid to the next lower tray. Gas or vapor to be supplied to treatment in a tower may, for example, be introduced through connection 10 and any gas

or vapor remaining uncondensed or unab-
sorbed may escape through connection 11. Liquid may be supplied through connection
12, and drawn off, together with any con-
stituents absorbed or condensed from the
gas or vapor, through connection 13. Em-
ployed as a fractionating tower, hot vapors
may be supplied through connection 10, a
condensed fraction separated in the tower
10 and drawn off through connection 13, and
the uncondensed vapors discharged through
connection 11. Employed as a scrubbing or
absorption tower, the scrubbing or absorbent
medium may be supplied through connection
15 12 while the gas or vapor mixture to be
treated is supplied through connection 10,
the absorbent or scrubbing medium charged
with absorbed constituents then being drawn
off through connection 13 and the stripped
20 gas or vapor mixture through connection 11.

The bubble caps illustrated in the drawing
are of cast metal. Referring partic-
ularly to Figs. 1 and 2, a series of projections
14 are arranged around the lower edge of
25 the side wall of the cap 15. Openings 16
for the escape of gas or vapor are provided
between each of these projections and open-
ings 17 for the escape of gas or vapor are
also provided at the outer end of these pro-
30 jections. The adjacent openings are thus
at a substantially different distance from the
vertical axis of the bubble cap, and a larger
area of opening is provided than is possible,
without sacrifice of the strength of the cap,
35 in a bubble cap of ordinary construction
with straight side walls. Referring partic-
ularly to Figs. 3 and 4, a series of projec-
tions 18 are provided on the side walls of
the cap 19. Openings 20 for the escape of
40 gas or vapor are provided in the side wall
of the cap between each of these projections
and a pair of openings 21 are provided in
the lateral walls of each of the projections.
The tops of the projections 18 are inclined
45 upwardly toward the vertical axis and in-
tersect with the side walls of the bubble cap
at a point appreciably higher than the upper
extremity of the openings 20 located directly
in the side of the main body of the bubble
50 cap.

Gas and liquid or vapor and liquid con-
tact apparatus equipped with bubble caps of
this type offer exceptionally low resistance
to the flow of fluids therethrough due to the
55 fact that the inclined tops of the projections
18 prevent the necessity of suddenly revers-
ing the direction of flow of the major por-
tion of the fluid entering through the nipple
7, and to the increased area of orifice open-
60 ings directly from the main body of the
bubble cap made possible by the increased
height of the openings into the projections
18. Here also, an increased area of opening
directly into the liquid is provided impossi-
65 ble in a cap of ordinary construction with

straight side walls. At the same time, gas
or vapor is discharged at a plurality of
points at different distances from the verti-
cal axis of the cap in angularly directed
streams promoting distribution and con-
tact. 70

While the bubble caps illustrated can
easily be fabricated by casting, and while
they are a particularly advantageous form
for cast bubble caps, it will be apparent that
bubble caps embodying the invention can be
fabricated in other ways. Likewise, the
bubble caps shown are generally of circular
configuration, but it will be apparent that
caps of various shapes, square, triangular,
80 hexagonal or rectangular may be constructed
embodying the invention.

One of the important advantages of the
bubble cap of the invention is that it pro-
vides for a high ratio between the total
width of opening for the discharge of gas
or vapor and the mean perimeter of the
bubble cap, or the perimeter of a bubble cap
of equal size of ordinary construction. In
the bubble cap illustrated in Figs. 1 and 2,
90 the total area of the opening for the escape
of gas or vapor is in excess of 0.5 square
inch per vertical inch of opening for each inch
of perimeter of the largest circle, the largest
regular geometrical figure, that can be drawn
95 within the points defined by the inner open-
ings, and in that illustrated in Figs. 3 and 4,
the total area of the opening on the basis
of the same comparison is in excess of one
square inch per vertical inch of opening. 100 Both of these caps, it will be noted, are
adapted to be supported on their rims. An-
other important advantage of the bubble
cap of the invention is that it provides for
such distribution of gas or vapor issuing
105 therefrom that any tendency to form large
bubbles with consequent reduction of contact
surface between gas or vapor and liquid is
minimized, insuring better contact and dis-
tribution. 110

In one aspect, the improved bubble cap of
the invention can be considered as making
available for contact with gas or vapor dis-
charge from each cap an annular ring of in-
creased radial thickness of liquid on the
115 tray in which the edge or rim of the cap is
submerged. Referring to Fig. 1, for ex-
ample, with a cap of ordinary construction
with straight side walls, escaping vapor
would be brought into contact only with
120 liquid immediately about the edge of the cap,
whereas with a cap constructed in accordance
with this invention escaping vapor is
brought into contact with liquid through-
out a zone at least as wide as the distance
125 between the inner openings 16 and the outer
openings 17.

I claim:

1. An improved bubble cap having irregu-
lar side walls with openings therethrough,
130

adjacent openings being non-adjoining and at substantially different distances from the vertical axis of the bubble cap:

2. An improved bubble cap having a series 5 of non-adjoining openings in the side walls thereof and an interposed series of openings projected a substantial distance beyond the first said series of openings, the openings of the last named series being non-adjoining 10 with respect to each other and to the openings of the first named series.

3. An improved bubble cap having side walls with alternate extensions and depressions with openings through both extended 15 and depressed portions thereof at substantially the same level and with openings from the main body of said bubble cap into the projecting portions thereof extending to a point substantially above the level of the 20 openings in the depressed portions of said side walls.

4. An improved bubble cap having side walls with alternate extensions and depressions with openings through both extended 25 and depressed portions thereof, the top of the extended portions inclining upwardly toward the vertical axis of the cap.

5. An improved bubble cap having side walls with alternate extensions and depres-

sions with openings through both extended 30 and depressed portions thereof the total area of the openings from the main body of the bubble cap into the extended portions being substantially in excess of the total area of the openings in the depressed portions. 35

6. An improved bubble cap having side walls with alternate extensions and depressions with openings in both extended and depressed portions thereof, and means for feeding gas downwardly from the crown 40 to the openings in said extended portions.

7. An improved bubble cap having side walls with alternate extensions and depressions, means for permitting the escape of gas from intermediate points in the side walls 45 of both extended and depressed portions, and means for withdrawing gas from the crown of said cap and transmitting it without sudden change in the direction of flow to the openings in the extended portions. 50

8. An improved bubble cap having a series of non-adjoining openings through the side walls thereof at substantially different distances from the vertical axis, said side walls having a substantial change in direction between consecutive openings. 55

In testimony whereof I affix my signature.
CLIVE M. ALEXANDER.
